BED DAVENPORT

Martin Fox, Chicago, Ill., assignor to The Seng Company, a corporation of Illinois

Application August 6, 1952, Serial No. 302,908

5 Claims. (Cl. 5—13)

This invention relates to a bed davenport, and in particular it relates to a bed davenport of the type in which a foldable bed frame composed of a plurality of pivotally connected bed sections extends forwardly of the davenport frame in bed position, and folds to a position within the frame.

The primary object of the invention is to provide a bed davenport in which the various elements of the unit are firmly held in davenport position.

A further object is to provide a bed davenport in which a longitudinal support bar underlies the mattress supporting spring structure of the bed and supports it above the floor in davenport position and is floatingly and resiliently suspended so that it does not interfere with the comfortable use of the bed, and in fact increases the comfort of the bed.

A further object is to provide a structure in which the seat frame is latched to the davenport frame in davenport position by latch means which may be readily disengaged by manipulation of a strap which overlies the seat frame in davenport position.

Yet another object is to provide a structure in which the rear of the seat frame is formed from a flat piece of resilient metal so as to provide a more comfortable unit to sit on.

The invention is illustrated in a preferred embodiment in the accompanying drawings in which:

Fig. 1 is a longitudinal sectional view of the improved davenport bed in davenport position;

Fig. 2 is a view similar to Fig. 1 showing the bed structure in a partially unfolded condition;

Fig. 3 is a fragmentary plan view of the device in bed position;

Fig. 4 is an enlarged sectional view taken as indicated along the line 4—4 of Fig. 3;

Fig. 5 is a sectional view taken as indicated along the line 5—5 of Fig. 3; and

Fig. 6 is a sectional view taken as indicated along the line 6—6 of Fig. 3.

Referring to the drawings in greater detail and referring first to Figs. 1 to 3, the bed davenport comprises a rectangular davenport frame indicated generally at 15, the main frame having end panels 16, arm structures 17, and an upright back structure 18. A front frame member 19 extends across the davenport frame and is suitably padded and upholstered.

As best seen in Fig. 1, the back structure 18 includes a back panel 20, a front bar 21 spaced a substantial distance forward of said panel 20, and end panels 22. A back cushion 23 for the davenport is of conventional spring and upholstered construction, and extends upwardly from the front bar 21 to provide a hollow, open bottom back structure for the davenport.

The bed structure and operating mechanism are substantially identical with those described in detail and claimed in my copending application Serial No. 63,412, filed December 3, 1948, now abandoned, and thus will be described only in enough detail to show the inter-

relationship of the novel elements and the old structure. Identical operating mechanisms are at the two sides of the bed structure, and only one will be described.

A pivot plate 24 secured to the end panel 22 of the back structure 18 pivotally supports a curved bed carrying arm 25 to which is attached the rear of a bed frame composed of four pivotally connected bed sections, each of which is preferably fabricated from angle stock. As best seen in Fig. 3 the bed sections include an intermediate bed section 26, flanking bed sections 27 and 28, and a forward bed section 29, all of which are connected together by suitable pivots. As best seen in Fig. 1, in davenport position the bed structure lies within the box-like davenport frame 15, the intermediate bed section 26 being at the bottom of the folded structure with the flanking bed sections 27 and 28 in upright positions at the rear and front, respectively, of the frame and the forward bed section 29 extending rearwardly from the top of the bed section 28 above and in spaced relation to the intermediate bed section 26. A conventional mattress supporting spring structure of wire, indicated generally at 30, is secured to the bed frame formed by the bed sections by means of coil springs 31 which are hooked to holes in the four pivoted bed sections in the usual fashion. A mattress, 32, shown in broken lines in Figs. 1 and 2, is supported on the spring structure 30 and is folded within the box-like enclosure formed by the pivoted bed sections in davenport position.

The operating and supporting mechanism for the folding bed structure includes a main pivot plate 33 which is secured to the davenport frame 15, and a linkage mechanism, indicated generally at 34, which is pivoted on the main pivot plate 33 and is pivotally connected to the intermediate bed section 26 and the flanking bed section 27. A seat frame 35 has a pivot plate 36 at its forward end and is operatively connected to the operating linkage 34 by a pair of links 37 and 38 and is connected to the flanking bed section 28 by means of a link 39 which has an extension 40 forming a supporting leg for said flanking bed section in bed position. As seen in Fig. 1, in davenport position the seat frame 35 is supported on a pair of brackets 41 which are fastened to the end panels 16 of the davenport frame and have projecting supporting arms 42. The linkage 34 and links 37, 38 and 39 are so constructed and arranged that the entire bed structure and seat frame 35 may be moved from the davenport position of Fig. 1 to the bed position of Fig. 3 merely by grasping the rear of the seat frame 35 and swinging it forward about the front frame member 19 of the davenport frame as far as it will go, in which position the intermediate bed section 26 and flanking bed section 27 are in bed position while the flanking bed section 28 and forward bed section 29 have maintained their relative positions with respect to the intermediate bed section 26, and the seat frame 35 is hanging in an upwardly and forwardly inclined position forward of the davenport frame 15, in which position it is hung from the link 39. The unfolding may then be completed by grasping the forward bed section by its foot rail 43 and drawing said bed section upwardly and forwardly so as to place the flanking bed section 28 and forward bed section 29 in a position coplanar with the bed sections 26 and 27. During this second portion of the movement to bed position the seat frame 35 assumes a horizontal position with the leg 40 on the floor, and a supporting leg 44 on the forward bed section 33 is swung into a vertical position beneath said bed section by means of a link 45. To retract the bed structure it is necessary only to follow the reverse operation, first folding the flanking bed section 28 and forward bed section 29 to their collapsed positions with respect to bed sections 26 and 27 and thereafter grasping the seat frame 35 to

complete the movement of the unit to the davenport position shown in Fig. 1. A counterbalancing spring 46 assists in the initial movement of the bed structure from davenport position to bed position.

All of the foregoing mechanism is disclosed in detail in my previously identified copending application, and it is the particular structure which will now be described which constitutes the improvement on said bed davenport structure. The thickness of the mattress which is used in modern bed davports, combined with the very low seat height of modern davports requires that the entire structure be very compactly disposed in davenport position, and in particular the intermediate bed section 26 which is at the bottom of the folded structure in davenport position is so close to the floor that the center portion of the bed spring 30 frequently sags until it touches the floor, leaving an imprint on the carpet or damaging the flooring as the davenport is moved about while cleaning. Likewise, the thickness of the mattress and bedding exerts a considerable force tending to unfold the bed sections and force the seat frame 35 to a forwardly tilted position. Thus, it is desirable to hold the bed spring 30 up and the seat frame 35 down in davenport position so as to provide a compact structure.

The flanking bed sections 27 and 28 are provided, respectively, with cross bars 47 and 48, respectively, which are spaced from the pivotal connections of said bed sections with the intermediate bed section 26. The cross bars 47 and 48 are straight so that the spring structure 30 lies on them, and are so positioned that the torso of a person occupying the bed may lie between them so that they cause no discomfort. The bars are about three feet apart, and the bar 47 is no more than 18 inches from the head of the bed. The very rigid construction afforded by the use of the straight cross bars 47 and 48 substantially eliminates bowing of the sides of the bed frame which is caused by the heavy pull (700 to 800 pounds) of the bed spring when the bed is occupied by two average people. It also substantially eliminates twisting of the frame during folding and unfolding, eliminating undesirable strain on the pivots for the bed frame and operating linkage. The bracing cross bars 47 and 48 also serve as supports for a longitudinal support bar 49 which is floatingly and resiliently suspended beneath that portion of the spring 30 which is within the confines of the intermediate bed section 26. As best seen in Figs. 3 to 6, the support bar 49 is a channel member having flared end portions 50 and 51 provided with holes 52 and 53, respectively, to receive, respectively, a hook member 54 and a pair of tension springs 55 which are hooked into said apertures and engage the cross bars 47 and 48, respectively, to provide the floating and resilient suspension for the support bar 49. The hook 54 is formed from a single piece of wire which is bent to provide spaced side members 56 and a transverse hook portion 57 which engages the cross bar 47, each of the side members 56 terminating in a hook 58 which engages one of the apertures 52 in the flared end 50 of the longitudinal support bar 49. The springs 55 are hooked at one end into the holes 53 in the flared end 51 of the support bar 49, and at the other end into holes in the cross bar 48. As seen in Fig. 1, when the bed structure is folded within the davenport frame 15 the projection of the bed spring 30 where it folds at the pivot between the bed sections 26 and 28 forces the springs 55 for the support member 49 outwardly to a small degree, and the hook 54 is drawn against the fabric of the spring 30 at the pivot between the bed sections 26 and 27 so that the springs 55 are somewhat tensioned so as to support the bed spring 30 and hold it off the floor. This also prevents sagging of the center of the davenport seat when a heavy person is seated on it. When the unit is in bed position the tension on the springs 55 is slightly released, and in addition the resilient mounting of the support bar 49 permits it to sag slightly

5 with the spring 30 under the weight of a person occupying the bed so that the support bar 49 causes no discomfort to the occupant of the bed. However, it still supports the spring 30 in such a way as to prevent spring sag, and two people occupying the bed do not roll together in the center as is true in a conventional double bed.

10 As best seen in Fig. 1, the seat frame 35 has end rails 35a formed of angle members which have their horizontal legs 35b uppermost, and a rear rail 59 formed of thin, 15 resilient metal so that it may bend slightly under the weight of a person sitting on the cushions of the davenport; thus materially increasing the comfort of the seat as against the usual seat frame structure in which the rear rail of the seat frame is formed of a rigid angle member. As best seen in Fig. 3, a fabric member 60 is supported by springs 61 in the seat frame 35 to support the davenport cushions.

20 Preferably the seat frame 35 is provided with latches 62 which make snap engagement with the horizontal leg 42 of bracket 41 on which the seat frame rests in davenport position, so that the upward thrust of the mattress and bed clothes does not tend to tilt the seat frame forward. The latches 62 may be released by pulling on a web strap 78 which extends across the top of the seat frame.

25 The foregoing detailed description is given for clearness of understanding only and no unnecessary limitations are to be understood therefrom, as some modifications will be obvious to those skilled in the art.

I claim:

30 1. In a folding and retractable bed structure for a bed davenport having a box-like frame, a plurality of pivotally connected bed sections including an intermediate bed section between a pair of flanking bed sections, said bed sections being adapted to be swingably supported on said frame for movement from a coplanar bed position projecting forwardly of the frame to a folded davenport position within the frame with said intermediate bed section at the bottom of the folded structure, a mattress-supporting spring structure secured to said bed sections, a cross bar on each flanking bed section which is spaced from the pivotal connection of said bed section with the intermediate bed section, and a support bar extending longitudinally of the bed structure which is suspended from said cross bars on a pivoted member at one end and on tension spring means at the other end, said support bar being so positioned as to support the portion of said spring structure which is within the intermediate section.

35 2. The bed structure of claim 1 in which the pivoted member has a pair of laterally spaced arms, and the tension spring means comprises a pair of tension springs which diverge laterally away from said bar.

40 3. In a folding and retractable bed structure for a bed davenport having a box-like frame; a plurality of pivotally connected bed sections including an intermediate bed section between a pair of flanking bed sections, said bed sections being adapted to be swingably supported on said frame for movement from a coplanar bed position projecting forwardly of the frame to a folded davenport position within the frame with said intermediate bed section at the bottom of the folded structure; a mattress-supporting spring structure secured to said bed sections; a cross bar on each flanking bed section which is spaced from the pivotal connection of said bed section with the intermediate bed section; an inextensible support bar extending longitudinally of the bed structure between said cross bars; and means resiliently and pivotally connecting the ends of said support bar to the cross bars substantially in contact with the underside of said spring structure, whereby said support bar supports the portion of said spring structure which is within the intermediate section.

45 4. In a folding and retractable bed structure for a bed davenport having a box-like frame; a plurality of pivotally connected bed sections including an intermediate

bed section between a pair of flanking bed sections, said bed sections being adapted to be swingably supported on said frame for movement from a coplanar bed position projecting forwardly of the frame to a folded davenport position within the frame with said intermediate bed section at the bottom of the folded structure; a mattress-supporting spring structure secured to said bed sections; a straight cross bar on each flanking bed section which is spaced from the pivotal connection of said bed section with the intermediate bed section and positioned substantially against the underside of the spring structure; an inextensible support bar extending longitudinally of the bed structure between said cross bars; and means resiliently and pivotally connecting the ends of said support bar to the cross bars substantially in contact with the underside of said spring structure, whereby said support bar supports the portion of said spring structure which is within the intermediate section.

5. In a folding and retractable bed structure for a bed davenport having a box-like frame; a plurality of pivotally connected bed sections including an intermediate bed section between a pair of flanking bed sections, said bed sections being adapted to be swingably supported on said frame for movement from a coplanar bed position projecting forwardly of the frame to a folded davenport position within the frame of said intermediate bed sec-
